UNITED STATES PATENT OFFICE.

CONYERS BUTTON, OF PHILADELPHIA, PENNSYLVANIA.

DESIGN FOR STOCKING FABRIC.

Specification forming part of Design No. 6,668, dated May 27, 1873; application filed May 13, 1873.

To all whom it may concern:

Be it known that I, CONYERS BUTTON, of the city and county of Philadelphia, State of Pennsylvania, have invented a Design for a Stocking Fabric, of which the following is a specification:

The figure in the accompanying drawing represents sufficient of a stocking fabric to fully illustrate my design, which consists of alternate light and dark stripes A and B, each composed of a series of minor parallel stripes, bars, or ribs, of different shades or colors, arranged in the manner clearly shown in the drawing.

If desired, the stripe A may be dark and the stripe B light, instead of the reverse, without departing from my design.

Irrespective of the colors employed, I claim—

The design for a stocking fabric, substantially as described, and as represented in and by the accompanying drawing.

In testimony whereof I have signed my name to this specification in the presence of two subscribing witnesses.

CONYERS BUTTON.
